United States Patent Office

Des. 173,651
Patented Dec. 14, 1954

173,651

HIGH CHAIR

Mac Gelman, Chicago, Ill., assignor to Comfort Lines,
Inc., Chicago, Ill., a corporation of Illinois

Application February 23, 1954, Serial No. 29,169

Term of patent 3½ years

(Cl. D15—1)

Fig. 1.

Fig. 2.

To all whom it may concern:

Be it known that I, Mac Gelman, a citizen of the United States, residing at Chicago, in the county of Cook and State of Illinois, have invented a new, original, and ornamental Design for a High Chair, of which the following is a specification, reference being had to the accompanying drawing, forming part thereof.

I claim:

The ornamental design for a high chair, substantially as shown.
